[57] CLAIM

The ornamental design for a lipstick case, as shown and described.

DESCRIPTION

FIG. 1 is a perspective view of a lipstick case showing my new design;

FIG. 2 is a front elevational view thereof, the rear elevational view appearing the same;

FIG. 3 is a left side elevational view thereof, the right side elevational view appearing the same;

FIG. 4 is a top plan view thereof;

FIG. 5 is a bottom plan view thereof; and,

FIG. 6 is a perspective view shown in an open position. The broken line showing of lipstick in FIG. 6 is for illustrative purposes only and forms no part of the claimed design.
